HEADREST ATTACHMENT

Floyd N. Cowman, Beverly Hills, Calif.

Application January 19, 1939, Serial No. 251,823

2 Claims. (Cl. 155—176)

This invention relates to an improved attachment for use with headrests of barbers' chairs and comprises a yieldable and resilient pad having means for detachably connecting it to a headrest 5 for positioning the pad over the coil springs thereof to provide a comfortable head support.

It is a primary object of this invention to provide a cushioning pad for headrests of barbers' chairs on which a customer's head may be comfortably rested so that the customer may relax 10 while being shaved or while head treatments or facials are being administered.

Other objects and advantages of the invention will hereinafter become more fully apparent from 15 the following description of the drawing, which illustrates a preferred embodiment thereof, and wherein—

Figure 1 is a plan view, partly broken away, showing the attachment mounted on a conventional head rest,

Figure 2 is a side elevational view of the same, and

Figure 3 is a vertical sectional view taken along the line 3—3 of Figure 1.

Referring more particularly to the drawing, wherein like reference characters designate like or corresponding parts throughout the different views, 10 designates generally a headrest of conventional construction and adapted for use with barbers' chairs, and including the corresponding end members 11, adjustment screw 12 and paper holding spindle or rod 13. The end members 11, which are suitably spaced from each other, are provided along their top edges with recesses 14 25 out of which project hooks 15 adapted to engage the hooked ends 16 of the contractile coil springs 17 which extend between the end members 11 to provide a yieldable headrest. These parts which have heretofore been described are all of 30 conventional construction and have been shown and described merely to illustrate the application of the invention which will hereinafter be described and which is adapted for use with a conventional headrest such as the headrest designated generally 10.

The attachment comprising this invention includes a relatively thick strip of cushioning material which is yieldable and resilient, such as sponge rubber, said strip, designated generally 18 35 being enclosed in a cover or casing 19 which is relatively thin and may be formed of any suitable material, preferably rubberized silk. Strip 18 and casing 19 combine to form a cushioning pad adapted to be disposed on top of the springs 17 and 40 to extend the length of the headrest 10 so that the ends of the pad will overlie and cover the top edges of the end members 11 to combine with the springs to form a soft yieldable support for the head which is of sufficient thickness to prevent the 45 user from feeling the coil springs 17 when the

head is resting on the pad. A plurality of straps 20, preferably formed of an elastic material, are secured, intermediate of their ends, to the under side of the casing 19 adjacent the ends thereof, as best illustrated in Figures 1 and 3. Straps 20 5 may be secured to casing 19 in any suitable manner, not shown, and are arranged in pairs, each pair of the straps 20 being provided at their free ends with a hook 21 and an eyelet 22.

It will thus be seen that when the pad is positioned on the springs 17 the free ends of the straps 20 may be connected by means of the hooks 21 and eyelets 22 beneath the springs 17, as illustrated in Figure 3, to hold the pad in position on the headrest 10 and to provide means whereby 15 it may be readily detached therefrom. The longitudinal edges of the strip 18 are bevelled on their outer sides as indicated at 23 so that the free end of a roll of paper, not shown, mounted on spindle 20 13 may be stretched over the top of the pad in the conventional manner, with its free end held at the top of the headrest 10 in a conventional manner, not shown.

Various modifications and changes in the precise construction and arrangement of the parts 25 forming the invention are contemplated and may obviously be resorted to, and the right is reserved to make such variations and changes as fall within the spirit and scope of the invention as herein-after defined by the appended claims. 30

I claim as my invention:

1. A headrest attachment for barbers' chairs, said attachment comprising a relatively thick pad of yieldable cushioning material, a casing enclosing said pad, a plurality of straps, of an elastic material having their intermediate portions, secured to the under side of said casing and transversely thereof, means for detachably connecting the free ends of said straps, said strap ends being 35 adapted to be connected under the head supporting portion of the headrest for detachably mounting the pad thereon.

2. An attachment for use with headrests for barbers' chairs, said attachment comprising a relatively thick pad of sponge rubber tapered on its outer side and along its longitudinal edges, a casing enclosing said pad, said pad and casing being adapted to be mounted on the coil springs of a headrest, and straps having intermediate portions secured to the under side and transversely of said pad and adjacent its ends, said straps being provided with means at their free ends for detachably connecting the strap ends beneath said coil springs for detachably mounting the pad 50 thereon, said straps being formed of an elastic material for yieldably holding the pad in engagement with the headrest springs. 55
